Henry Whitney's Design for Intestine and Pen-Nack

Nº 3723

PATENTED
OCT 19 1869

United States Patent Office.

HENRY WHITNEY, OF EAST CAMBRIDGE, MASSACHUSETTS

Design No. 3,723, dated October 19, 1869.

DESIGN FOR A COMBINED INKSTAND AND PEN-RACK.

The Schedule referred to in these Letters Patent and making part of the same.

To all whom it may concern:

Be it known that I, HENRY WHITNEY, of East Cambridge, in the county of Middlesex, and State of Massachusetts, have invented a new Design for a Combined Inkstand and Pen-Rack, of which the following is a full, clear, and exact description, reference being had to the accompanying drawing, which represents a perspective view of my design.

My invention has for its object to produce an ornamental and unique design for an inkstand and pen-rack, and consists in a dome-shaped receptacle, from the top of which rises a pair of notched standards, forming a pen-rack, a recess being formed in the side of the said receptacle, in which to place a dipping-cup.

To enable others skilled in the art to understand and use my invention, I will proceed to describe the manner in which I have carried it out.

In the said drawings—

A represents a hollow dome, which is intended as an

inkstand, in which is formed a recess, B, provided with an orifice, which serves as a dipping-cup, the latter being provided with a cap or cover, a.

The exterior of the dome, from its central highest point down to a bead, b, at its base, is composed of a series of fluted surfaces, c, crossed by a pair of upright standards, C, in which is formed a series of notches, d, which serve as a rack to support pens or pencils.

Claim.

What I claim as my invention, and desire to secure by Letters Patent, is—

The within-described design for a combined inkstand and pen-rack, substantially as shown.

HENRY WHITNEY.
